CLAIM

We claim the ornamental design for a synchronization cradle for a handheld computer, as shown and described.

DESCRIPTION

FIG. 1 is a perspective view of a synchronization cradle for a handheld computer showing our new design, the broken line disclosure is for illustrative purposes only and forms no part of the claimed design;

FIG. 2 is a right side elevation view thereof;

FIG. 3 is a front elevation view thereof;

FIG. 4 is a top plan view thereof; and,

FIG. 5 is a rear elevation view thereof.

1 Claim, 5 Drawing Sheets
